SCOPE LENS PROTECTOR

Rudy T. Saari, Ontonagon, Mich. 49953, and Eino F. Kananen, Box 57, Bruce Crossing, Mich. 49912

Filed Oct. 3, 1966, Ser. No. 4,131

Term of patent 14 years

(Cl. D22—13)

The dotted line illustration of the scope sight in FIGURE 1 is to show the new design in use for illustrative purposes only.

We claim:

The ornamental design for a scope lens protector, as shown and described.
